UNITED STATES PATENT OFFICE

2,393,401

ROOF CONSTRUCTION

Arthur F. O'Connor, Chicago, Ill., assignor to
 Union Asbestos & Rubber Company, a corpora-
 tion of Illinois

Application March 20, 1944, Serial No. 527,202

4 Claims. (Cl. 108—5.4)

This invention relates to roof construction and more particularly to a roof construction for railway cars and the like.

One of the objects of the invention is to provide a roof construction in which the joints between adjacent roof sheets are tightly sealed at the eaves of the car.

Another object is to provide a roof construction formed by a plurality of roof sheets in which water-tight joints are provided between adjacent sheets throughout their full length.

Still another object of the invention is to provide a roof construction which is easy and inexpensive to manufacture and install, either as a new roof or as a replacement.

The above and other objects and advantages of the invention will be more clearly understood by reference to the following description when read in connection with the accompanying drawing in which:

Fig. 1 is a partial plan view of a car roof embodying the invention;

Figs. 2 and 3 are enlarged sections on the lines 2—2 and 3—3 respectively of Fig. 1; and

Fig. 4 is a partial section on the line 4—4 of Fig. 2.

The roof illustrated is adapted to be installed on a railway car having side plates 10 extending along the length of the car and formed by Z-shaped bars having upstanding inner flanges rolled over, as indicated at 11, to support the roof. The roof is formed by a plurality of sheets 12 of metal or the like laid across the side plates and connected by transversely extending seams.

The plates are joined by forming each plate at its opposite edges with an upstanding flange 13 which are butted together. The flanges 13 terminate in a sloping edge 14 adjacent the ends of the sheet to leave a plane portion 15 of the sheet extending across the side plates and downwardly thereover. When the sheets are assembled the flanges are placed face to face and the portions 15 of the sheets meet in a plane butt-joint. The flanges are covered by seam covers 16 which are channel shaped to fit over the flanges and which have skirt portions 17 partially overlying the upper surfaces of the sheets. The flanges and seam covers are joined by fastenings such as rivets 18 extending therethrough.

The seam covers terminate at their ends in downwardly extending portions 19 overlying the portions 15 of the sheets and terminating adjacent the lower ends of the portions 15. The seam cover portions 19 are closed at their lower ends by closure plates 21, welded or otherwise se-

cured therein, to form closed pockets overlying the butt-joints between the sheet portions 15.

In order to seal the joints between portions 15 at the eaves of a car against moisture, the downwardly extending portions 19 of the seam covers are filled with a sealing material. As shown, such material may be forced into the seam covers after assembly through openings therein closed by plugs 22. Preferably a plastic, non-drying, sealing material is employed such as an asphalt or tar composition mixed with a non-drying oil or plasticizer, or a gum or wax compound such as that sold commercially under the trade name "Permagum." This material is forced into the seam cover in sufficient quantity to extend up over the eaves of the car, as shown at 23 in Fig. 3. Thus it effectively seals the joint between the portions 15 of the roof sheets as well as the ends of the flanges 13 to prevent moisture from getting into the car at the eaves.

While one embodiment of the invention has been shown and described in detail herein, it is understood that this is illustrative only and is not intended as a definition of the scope of the invention, reference being had to the appended claims for that purpose.

What is claimed is:

1. A roof construction for a car or the like having parallel side plates comprising a plurality of roof sheets extending across the side plates and having abutting upstanding flanges at their adjacent edges, a channel shaped seam cover fitting over the flanges of each pair of sheets and terminating at its ends in hollow closed portions extending downwardly around the side plates and including the seams between adjacent side plates, and plastic sealing material filling said portions and sealing the seams between the roof sheets.

2. A roof construction for a car or the like having parallel side plates comprising a plurality of roof sheets extending across the side plates and having abutting upstanding flanges at their adjacent edges, said flanges terminating substantially in alignment with the side plates and the roof sheets including portions extending across the side plates and downward thereover, a channel shaped seam cover fitting over the flanges of each pair of sheets and having downwardly extending hollow portions overlying said portions of the roof sheets, and plastic sealing material filling said hollow portions of the covers to seal the joints between the downwardly extending portions of the sheets.

3. A roof construction for a car or the like

having parallel side plates comprising a plurality of roof sheets extending across the side plates and having abutting upstanding flanges at their adjacent edges, said flanges terminating substantially in alignment with the side plates and the roof sheets including portions extending across the side plates and downward thereover, a channel shaped seam cover fitting over the flanges of each pair of sheets and having downwardly extending hollow portions overlying said portions of the roof sheets, means closing the lower ends of said portions of the channels to form pockets overlying the joints between the downwardly extending portions of the sheets, and plastic sealing material filling said pockets.

4. A roof construction for a car or the like having parallel side plates comprising a plurality of roof sheets extending across the side plates and having abutting upstanding flanges at their adjacent edges, a channel shaped seam cover fitting over the flanges of each pair of sheets and terminating at its ends in hollow closed chambers inclosing the seams between the edge portions of adjacent side plates, and plastic sealing material filling said chambers and sealing the seams between the roof sheets, said seam cover having an aperture therein opening into the hollow closed chambers and closure means removably secured in the aperture.

ARTHUR F. O'CONNOR.

CERTIFICATE OF CORRECTION.

Patent No. 2,393,401.

January 22, 1946.

ARTHUR F. O'CONNOR.

It is hereby certified that error appears in the printed specification of the above numbered patent requiring correction as follows: Page 1, second column, line 36, for "including" read --inclosing--; and that the said Letters Patent should be read with this correction therein that the same may conform to the record of the case in the Patent Office.

Signed and sealed this 9th day of April, A. D. 1946.

Leslie Frazer
